UNITED STATES PATENT OFFICE.

LARS MORRIS MOCHAU, OF EAST HARTFORD, CONNECTICUT.

AUTOMATIC DOOR-RELEASING APPARATUS.

1,165,436.

Specification of Letters Patent. Patented Dec. 28, 1915.

Application filed November 27, 1914. Serial No. 874,146.

To all whom it may concern:

Be it known that I, LARS MORRIS MOCHAU, a citizen of the United States, residing at East Hartford, in the county of Hartford and State of Connecticut, have invented a new and useful Improvement in Automatic Door-Releasing Apparatus, of which the following is a specification.

It is desirable to have the doors of school buildings, theaters, churches, halls and like places of public assemblage and entertainment, fastened in such manner that they can be instantly opened outward in case of fire or panic.

15 This invention relates to an apparatus which is so designed that the doors of such places can from different localities, without effort, be instantly released and opened.

The object of the invention is to provide 20 apparatus by means of which one or more doors that are normally held closed will be automatically released and swung open whenever pressure is applied to them from the interior, as when persons push against 25 them, or when a button at a distance is pressed, or a fire alarm is sounded. This object is attained by covering considerable 30 surface of the doors with push plates that when pressed against will close an electrical circuit to release the retaining latches and bolts, which circuit may be extended any 35 distance and provided with push buttons at various strategic localities, or may be connected by relay with a fire alarm circuit, in such manner that when a button is pushed or the alarm is set in action the latches and bolts will be released the same as when the doors are pushed against.

Figure 1 of the accompanying drawings 40 shows in elevation a double door provided with latch and bolts which are designed to be released by pressure on push plates carried by the doors, or by the push of a button, or by the sounding of an alarm, the 45 electrical connections for accomplishing this being indicated in diagram. Fig. 2 shows a section of one of the doors taken through the push plate and the electrically released latch-catch. Fig. 3 shows a view of the 50 back and Fig. 4 a view of the side of contacts which may be arranged in the hanging jamb of the door casing to insure the continuity of the circuit between the casing and the door when the latter is closed. Fig. 5 shows a side view and Fig. 6 shows a back

view of contacts which may be arranged in the hanging stile of the door for insuring the completion of the circuit between the casing and the door. Figs. 7, 8 and 9 show edge, side and top views of one of the automatic bolts which may be employed for retaining the doors shut. Fig. 10 shows a side view, Fig. 11 a face view and Fig. 12 a cross section of the latch-catch and the electrically actuated mechanism for releasing the latch when the circuit is closed by pressure on the push plates, buttons, or the sounding of the alarm. Fig. 13 shows a view of a form of pusher that may be used for throwing open the doors when the latch and bolts are released by the closing of the circuit.

The invention is illustrated as applied to a set of double doors 1 and 2, which are hung in the usual way so as to open outwardly. The door 1 may, as shown, be provided at top and bottom with retaining bolts 3. The bolts illustrated are of the type shown in U. S. Patent No. 946,764, January 18, 1910. Such a bolt is normally retracted into its frame 4 by a spring 5 and is forced 60 outward into a socket in the door casing by the engagement with the pin 6, which extends out from the bolt through an inclined slot 7, of the edge of the opposing door when the doors are closed. When the door 2 is 65 released the springs draw in the bolts that hold the door 1, and the slots turn the pins so they tend to throw open the door 2. To further aid in throwing open the doors when the latch and bolts are released pushers 70 consisting of a socket 8, ball 9 and spring 10 may be placed in the casing jambs so as to thrust against the edges of the hanging 75 stiles of the doors.

One of the doors, 2, is provided with a 80 common form of latch 11 and knob 12 so as to enable the door to be opened in the customary way. The other door, 1, is provided with an electrically released catch 13 for retaining the latch. This device is of the type 85 which forms the subject of U. S. Patent No. 538,127, April 23, 1895. Such a catch is pivotally mounted in its frame 14 and is normally held rigid by a rocker 15 that is engaged by a trip 16 that is disengaged by 90 the pull of the magnets 17 when the circuit 95 in which the magnets are connected is closed.

On the face of each door, and covering 100 considerable surface is a push plate 18 that is guided by pins 19 and is pushed out by 105

110

springs 20. These plates carry contact studs 21 that are connected with each other by means of the wire 22. A wire 23 connects one of the studs 21 on the door 1 with one terminal of the catch releasing field magnet 17. In the doors back of the studs are contacts 24 which by wires 25 and 26 are connected with one pole of the battery, or other source of electrical energy 27. The other pole of the battery is connected by a wire 28 with the other terminal of the catch magnets 17. When either of the plates is pushed in by pressure against them the power circuit is closed and the magnets cause the release of the catch and the freeing of the latch so the doors will of themselves swing open or will be pushed open by the pressure against the push plates. The circuit may also be closed to accomplish the same result by pushing buttons 29, of which there may be any number placed at any desired distant locality. The circuit wires may also be led to an automatic closer consisting of a magnet 30 in a fire alarm circuit 31, and a circuit closer 32 that is caused to close the door circuit when the magnet 30 is energized by current incident to the operation of the alarm.

In order to insure the continuity of the circuit from the casing to the doors spring projected contact pins 33 connected with the wires may be arranged in the casing jamb or the hanging stile of the doors so as to make engagement with plates 34 connected with the wires and located in the opposing part when the doors are closed. These spring pins also aid in throwing open the doors when the catch is released.

By means of this apparatus pressure against the doors in an outward direction, the pushing of a button, or the sounding of an alarm will instantly cause the doors to swing fully open, and permit free exit therethrough.

45 The invention claimed is;

1. The combination with a door of an electrically released catch carried thereby, fixed and movable contacts carried by the door and normally held disengaged, and an open electric circuit including the catch operating mechanism and the fixed and movable contacts, said circuit being adapted to be closed by pressure applied to the movable contacts.

50 2. The combination with a door of an electrically released catch, fixed and movable contacts carried by the door, springs for normally holding the movable contacts out of engagement with the fixed contacts, a plate adapted to be pushed for causing the movable contacts to engage with the fixed contacts, and an electric circuit including the catch operating mechanism and the

fixed and movable contacts carried by the door.

55 3. The combination with a pair of doors of a latch on one door, an electrically released catch on the other door, fixed and movable contacts carried by the doors, springs normally holding the contacts disengaged, push plates carried by the doors for causing the engagement of the contacts, and a normally open electric circuit including the catch operating mechanism and the fixed and movable contacts, said circuit being adapted to be closed by pressure on either of the plates.

70 4. The combination with a door of an electrically released catch, fixed and movable contacts carried by the door, springs for normally holding the contacts disengaged, a plate for causing the engagement of the contacts, a normally open electric circuit including the catch operating mechanism and the fixed and movable contacts 85 carried by the door, and push buttons at a distance from the door, whereby the circuit may be closed by pressing the plate or the button.

75 5. The combination with a door of an electrically released catch, fixed and movable contacts carried by the door, means for normally holding the contacts disengaged, a plate by means of which the contacts may be engaged, an electric circuit including the catch operating mechanism and the fixed and movable contacts, and an electrically operated circuit closer, whereby the circuit may be closed by pressure on the plate or by a flow of current through the circuit 100 closer.

6. The combination with a door of an electrically released catch, fixed and movable contacts carried by the door, push buttons arranged at a distance from the door, 105 an electrically operated circuit closer arranged at a distance from the door, and a normally open electric circuit comprising the catch operating mechanism and the fixed and movable contacts carried by the door, 110 also the push buttons and the electrically operated circuit closer, whereby the circuit may be closed by pushing in the movable contacts on the door, or by pressure on the push button, or by the closing of the circuit 115 by the action of the electrically operated circuit closer.

7. The combination with a door of an electrically released catch, an electric circuit including the catch operating mechanism, and a push plate carried by the door for closing said circuit.
